CLAIM

The ornamental design for a shelving unit post with keyhole as shown and described.

DESCRIPTION

FIG. 1 is a top left front isometric view of shelving unit post with keyhole showing my new design.

FIG. 2 is an enlarged top left front isometric view thereof.

FIG. 3 is a top right front isometric view thereof.

FIG. 4 is a front elevation view thereof.

FIG. 5 is a top left front isometric view of shelving unit post with keyhole showing an alternative embodiment of my new design.

FIG. 6 is an enlarged top left front isometric view thereof.

FIG. 7 is a top right front isometric view thereof.

FIG. 8 is a front elevation view thereof.

FIG. 9 is a top left front isometric view of shelving unit post with keyhole showing another alternative embodiment of my new design.

FIG. 10 is an enlarged top left front isometric view thereof.

FIG. 11 is a top right front isometric view thereof.

FIG. 12 is a front elevation view thereof.

FIG. 13 is a top left front isometric view of shelving unit post with keyhole showing yet another alternative embodiment of my new design.

FIG. 14 is an enlarged top left front isometric view thereof.

FIG. 15 is a top right front isometric view thereof; and,

FIG. 16 is a front elevation view thereof.

The broken dash-dot lines in FIGS. 1-16 are included for the purposes of illustrating environment and form no part of the claimed design. Neither the portions of the shelving unit post with keyhole shown in broken dot-dash lines nor the broken dot-dash lines themselves form any part of the claimed invention.

The broken dash lines in FIGS. 5-7 and 13-15 depict portions of the shelving unit post with keyhole that form no part of the claimed design. Neither the portions of the shelving unit post with keyhole shown in broken dash lines nor the broken dash lines themselves form any part of the claimed invention.
